UNITED STATES PATENT OFFICE

105,559

DESIGN FOR A ROBE

Pauline Schnittman, New York, N. Y.

Application June 28, 1937, Serial No. 70,094

Term of patent 3½ years

To all whom it may concern:

Be it known that I, Pauline Schnittman, a citizen of the United States of America, residing in Manhattan, county of New York, and State of New York, have invented a new, original, and ornamental Design for a Robe, of which the following is a specification, reference being had to the accompanying drawing, forming part thereof, wherein,

I claim:

The ornamental design for a robe, substantially as shown.

PAULINE SCHNITTSMAN.
